BY

INVENTOR
John E. Long.
ATTORNEY

UNITED STATES PATENT OFFICE

JOHN E. LONG, OF MULTNOMAH, OREGON

GUIDING DEVICE FOR CIRCUIT CONTROLLERS

Application filed June 21, 1928. Serial No. 287,308.

My invention relates to electric circuit controlling apparatus and especially to that type adapted to control a plurality of circuits by a single tape-like insulating member perforated to cover and uncover a series of exposed terminals.

The principal object of my invention is to provide controlling apparatus of this character with means for guiding such tape so that 10 the perforations in the latter will be in absolute registration with the terminals and to accomplish this end with noiseless means which may be easily and quickly aligned and which do not produce a great amount of friction to 15 the passage of such tape-like control element as it passes over them.

A further object of my invention is to provide efficient means for eliminating dirt or other foreign matter from the control apparatus, which would interfere with its efficient operation by becoming attached to the 20 tape-like control member and to fill the perforations in the latter.

I attain such objects by providing a container, adapted to house such terminals and have such tape-like control elements lead therethru, with a removable cover to which are attached spaced pendent guide elements. The lower end of such guide elements are 25 formed into upwardly opening cups facing opposite the direction of motion of such tape and lying below the level of the liquid contained in such container, so as to catch the foreign material which collects as scum on 30 top of the liquid. Such liquid and the scum carried thereby are caused to flow by the movement of the tape and such scum flows into such cups and can be removed from the 35 liquid when the cover is removed from the 40 container.

Further details of construction and the mode of operation of my improved circuit controlling device are hereinafter described with reference to the accompanying drawings, in which:

Fig. 1 is a longitudinal fragmentary section thru such controlling apparatus;

Fig. 2 is a detail view of the cover with the pendent tape guiding elements carried thereby; and

Fig. 3 is a fragmentary plan view of such device showing the adjustable mounting for one of such guides.

My invention relates particularly to the circuit controlling apparatus shown in Re-issue Patent No. 16,809, granted December 9, 1927, to myself, and thus in this application I will not describe in detail all of such controlling apparatus, but only the parts specifically directed towards this improvement and reference is had to such re-issue patent for a description of the general structure and operation of the entire controlling apparatus.

Such controlling apparatus includes a container *a*, the bottom *a'* of which, at least, is made of insulating or non-conducting material, because in such bottom a plurality of terminals *b* are carried in predetermined pattern, the upper ends *b'* of such terminals being substantially flush with the inner surface of such bottom *a'*. The side walls *a*² of such container extend upwardly a substantial distance and a body of mercury *c*, or other similar liquid is contained therein. A cover *d* is carried by such container, the ends *d'* thereof not extending entirely to the end of the container so as to provide slots *e* thru which the tape-like control *f* can be led into the container, and out of the latter. Electrical connection is made between the terminals *b* and the source of electrical energy thru perforations in such tape *f*, the body of mercury *c* being in electrical circuit with a source of electrical energy thru a connection *g*. To utilize the maximum length of the bottom *a'* of such container, guides are provided at the ends of the latter to hold the tape-like control *f* against the bottom and the tape-like control element *f* makes a relatively sharp angle about such guides. Heretofore, as shown in such re-issue patent, I have provided rollers at the ends to serve as such guides, but because of such sharp angle, any slight lack of alignment with the guide rollers *h* at each end serves to lead the tape-like control element out of registration with the terminals *b*. This is evidently because the rolling contact of the guide rollers tend to "lead" the control element to permit the latter to assume a straight line between the guide

rollers *h* at each end. That is, such guide rollers within the container have a screw action when there is any lack of alinement. To overcome this difficulty and others, I provide guide elements *i* consisting of fixed pendent members carried by the cover *d*, the lower ends of which are formed into upwardly facing cups *j* with their forward edge slightly below the level of the body of mercury *c*. Such cup-like ends are faced to oppose the direction of motion of the tape-like control element *f* and such cups *j* are imperforate. One or both of such guides *i* are fastened to the cover by screws *k*, which pass thru slotted holes *l* so as to permit the guides *i* to be adjusted relatively to such cover and to be alined exactly. The outer surface of the guides *i* are highly polished to eliminate friction and the bottom of the cup-shaped ends *j* extend into transverse grooves *m* in the container bottom. The provision of such grooves *m* tends to hold the tape tightly upon the terminals and to prevent the conducting liquid *c* from entering thereunder.

As has been previously mentioned, there is a perceptible flow in the body of mercury *c* when the tape-like control element *f* is pulled therethru and foreign matters getting into such container form as a scum on top of such mercury and unless removed, such scum adheres to the tape-like control element to clog the perforations therein. Guide rollers tended to pull such foreign matter downwardly onto such tape while the provision of cups *j* tends to collect such material and if the cover *d* is lifted from time to time the scum collected in such cups *j* can be removed easily.

I claim:

1. In an electric circuit controlling device of the character described including a liquid container adapted to have a tape-like control element led therethru and along the bottom thereof, the combination of a removable cover for such container having a pendent transverse guide element for such control element arranged within such container, the lowermost portion thereof adapted to engage such control element, such portion being non-rotatable, and rounded in longitudinal section.
2. In an electric circuit controlling device of the character described including a liquid container adapted to have a tape-like control element led therethru and along the bottom thereof, the combination of a removable cover for such container having a pair of spaced, pendent, transverse guide elements for such control element arranged within such container, the lowermost portion thereof adapted to engage such control element, such portion being non-rotatable, and rounded in longitudinal section.
3. In an electric circuit controlling device of the character described including a liquid container adapted to have a tape-like control

element led therethru, the combination of a guide element for such control element arranged within such container, the lower end of such guide element forming an upwardly opening cup for the purpose specified.

4. In an electric circuit controlling device of the character described including a liquid container adapted to have a tape-like control element led therethru, the combination of a guide element for such control element arranged within such container, the lower end of such guide element forming an upwardly opening cup facing to oppose the direction of motion of such tape for the purpose specified.

5. In an electric circuit controlling device of the character described including a liquid container adapted to have a tape-like control element led therethru, the combination of a guide element for such control element arranged within such container, the lower end of such guide element forming an upwardly opening cup lying slightly below the level of the liquid in such container for the purpose specified.

6. In an electric circuit controlling device of the character described including a liquid container adapted to have a tape-like control element led therethru, the combination of a guide element for such control element arranged within such container, the lower end of such guide element forming an upwardly opening cup facing to oppose the direction of motion of such tape and lying slightly below the level of the liquid in such container for the purpose specified.
